UNITED STATES PATENT OFFICE.

HERBERT S. GREEN, OF ST. PAUL, MINNESOTA, ASSIGNOR TO SAINT PAUL FIRE & MARINE INSURANCE COMPANY, OF ST. PAUL, MINNESOTA, A CORPORATION OF MINNESOTA.

MANIFOLDING-PAD.

945,323.

Specification of Letters Patent.

Patented Jan. 4, 1910.

Application filed October 3, 1908. Serial No. 456,091.

To all whom it may concern:

Be it known that I, HERBERT S. GREEN, a citizen of the United States, residing at St. Paul, in the county of Ramsey and State 5 of Minnesota, have invented certain new and useful Improvements in Manifolding-Pads, of which the following is a specification.

My invention relates to improvements in manifolding pads for insurance policy 10 blanks and other documents where it is desired to take one or more exact impression copies of the original document, its object being to secure the sheets forming each set of original and duplicates to each other and 15 to the pad in such way that the set as a whole may be detached from the pad without detaching the separate sheets from each other or disturbing their relation to one another.

20 The invention is particularly designed for insurance policy blanks, as illustrated in the drawings, but may be applied to other documents which are handled in the same way.

Insurance policies are commonly written 25 by the agents upon standard printed forms supplied by the company, in which blank spaces are left to be filled in with the special facts of the particular risk to be underwritten. It is customary for the agent to 30 take a copy of the material parts of the policy for his own files and to send another copy to the company. This is done in various ways, but it will be evident that if the 35 copies are made by taking carbon impressions upon duplicate forms printed to correspond with the original, it is necessary to hold the sheets in exact alinement.

With the object of facilitating the operations herein referred to the invention 40 consists in the construction, combination and arrangement of parts hereinafter described and claimed.

In the accompanying drawings forming 45 part of this specification, Figure 1 is a vertical longitudinal section through a pad of sheets from which all but one set have been detached; Fig. 2 is a perspective view of a pad, partly broken away, with one set of sheets in course of removal, Fig. 3 is a perspective view of a fragment of a detached 50 set ready to receive entries; Fig. 4 is a detail showing the sheets in course of detachment from one another after the entries have been made; Fig. 5 is a perspective view 55 of a set of sheets with the sheets lifted from

one another and partly broken away, and Fig. 6 is a top view of a set of sheets partly broken away to show the alinement of the printed matter upon them.

Referring to the drawings, each manifolding set comprises a plurality of sheets arranged one upon another and pasted or otherwise secured together along one edge, preferably at the foot, to form a common securing strip 2. In the form shown in the 60 drawings, which is particularly adapted for double sheet insurance policies where two carbon impressions are to be taken, there are three such sheets 3, 4 and 5, respectively, and the bottom sheet 3 has an extension leaf 6, 70 which is folded over upon the face of the other sheets with its lower edge free. In this form the extension leaf thus becomes the "original" entry sheet, but it will be understood that however the sheets are 75 arranged the top sheet will necessarily be the original.

The securing strip is separated or set off from the main body of each of the sheets secured to it by a perforated or otherwise 80 weakened line 7. These lines register with one another so that all of the sheets can be torn off in a body from the securing strip, as illustrated in Fig. 4. One of these sheets, preferably the bottom sheet 3, as shown in 85 the drawings, is extended beyond the securing strip to form a terminal binding tab 8, which is separated from the strip by a weakened line 9.

Upon the face of the top sheet, here the 90 extension leaf 6, is printed the original policy or other document form, while upon one or more of the underlying sheets 4 and 5 is printed a duplicate or duplicates thereof. In assembling the sheets of each set, they are 95 placed one upon another so that the printed matter and blank spaces upon each sheet will register with the corresponding printed matter and blank spaces upon each of the other sheets, as shown in Fig. 6. In this way it is 100 possible to use printed blanks for the duplicate sheets. When the sheets are so assembled they are pasted together along one edge to form the securing strip as above described.

The sets so formed are then laid one upon 105 another and the alining tabs 8 are bound together by suitable means, such as the stitching 10 and binding 11 to form a pad. If desired, a backing 12 of stiff material may be bound up with the tabs, and this backing 110

may be folded over the sheets to form a flap 13.

It will be seen that the pad so formed affords a compact and convenient means for holding a number of sets of document blanks. When a policy or other document is to be written, the uppermost set is torn from the pad along the weakened line 9 between the tab and the securing strip, as illustrated in Fig. 2. After the sheets are detached from the pad they will still be held together by means of the securing strip 2. The sheets may then be lifted and carbon impression sheets 14 placed between them, as shown in Fig. 3. After the necessary matter has been filled in upon the original, or upper, sheet, the sheets may be torn as a whole from the securing strip along the weakened line 7, and the original and duplicate sheets separated and disposed of as may be desired.

20 I claim as my invention:

1. A manifolding pad comprising a plurality of sets of sheets, each set comprising an original sheet folded over upon itself and 25 a plurality of duplicate sheets arranged within said fold, the back leaves of the original sheets being bound together at their unfolded ends to make a pad, being formed near their bound ends with two parallel 30 spaced lines of scoring to form a detachable

securing strip, and the duplicate sheets being pasted at their lower ends upon the securing strip between said parallel scorings, and being formed with scored lines along the upper edge of the strip registering with 35 the upper scored line of the back leaf of the original sheet, whereby the securing strip can be detached as a whole so as to release from each other all of the sheets comprising the set.

2. A manifolding pad comprising a plurality of sets of original and duplicate sheets, the sheets of each set being secured together along one edge to form a common securing strip, and one of the sheets of each set having 40 a binding tab projecting beyond the securing strip, said sheets having substantially registering weakened lines along the inner side of the strip to facilitate the separation of the sheets therefrom, and each tab having 45 a weakened line along the other side of the strip to facilitate detachment of the set as a whole.

In testimony whereof I affix my signature in presence of two witnesses.

HERBERT S. GREEN.
